UNITED STATES PATENT OFFICE.

CHARLES W. BECK, OF ROCKVILLE CENTER, NEW YORK, ASSIGNEE, BY MESNE ASSIGNMENTS, TO THE BECK-FROST CORPORATION, OF DETROIT, MICHIGAN, A CORPORATION OF MICHIGAN.

TOOL-BOX FOR AUTOMOBILES.

1,263,343.

Specification of Letters Patent. Patented Apr. 16, 1918.

Application filed January 9, 1911, Serial No. 601,500. Renewed July 3, 1914. Serial No. 848,894.

To all whom it may concern:

Be it known that I, CHARLES W. BECK, a citizen of the United States, and resident of Rockville Center, county of Nassau, and 5 State of New York, have invented certain new and useful Improvements in Tool-Boxes for Automobiles, of which the following is a specification.

The main object of this invention is to 10 provide a simply constructed flat tool box made in two sections or parts, each part containing a block of filling having formed therein recesses or slots of various shapes and adapted to receive the usual machinists' 15 tools carried on automobiles for use in repairing and adjusting the various parts of the machine.

Another object of the invention is to line 20 the recesses in the filler with a suitable cushioning material so that the tools when placed therein will be held out of contact with the box sections.

Another object of the invention is to so 25 arrange the slots or recesses in the fillers that they may be cut inwardly from the ends of the fillers, whereby the device may be formed by sawing the slots or recesses.

Another object of the invention is to form 30 the fillers of two thicknesses of material, the slots for the thin tools, such as monkey-wrenches, being cut through only the uppermost layer, while the slots or recesses for the thick tools are cut through both of the layers or pieces.

35 Another object of the invention is to provide a substantial metal box formed of two sections hinged together and provided with wooden filler pieces suitably cut out to receive the tools, each of said box sections being lined with felt, said felt being held in position by the wooden filler pieces and serving to cushion the tools in the slots or recesses.

There are other important objects and 45 advantages of the invention which will appear hereinafter.

In the drawings Figure 1 is a plan view of the box open;

Fig. 2 a transverse sectional view on the 50 line II-II of Fig. 1;

Fig. 3 a similar view showing the box closed; and

Fig. 4 a transverse sectional view on the line IV-IV of Fig. 1, showing the means

for fastening the metal box to the wooden 55 filler pieces.

Referring to the various parts by numerals, 1 and 1^a designate the two box sections which are substantially equal in area and are hinged together along one longitudinal 60 edge as at 3, the section 1 constituting the main box section and the section 1^a constituting the cover section. Each box section is formed preferably of sheet metal and is lined with a sheet of cushioning felt 4. 65 This felt preferably only covers the bottom of the main box section 1 and the under side of the top of the cover section 1^a. In the cover section 1^a is fitted a filler block or piece 5 of wood or other suitable material whose 70 upper surface is only slightly below or within the free edges of the sides of said section. In this filler block are formed slots 6 of various shapes and designed to receive the various machinists' tools which are usually 75 carried on automobiles. These slots are cut inwardly from the ends of the filler block, as shown clearly in Fig. 1 so that said slots may be formed by means of a saw. The filler block 5 of the cover section is provided 80 with rotatably mounted retaining hooks 7 which are adapted to be turned over the tools and to retain them in place. One of these retaining hooks is shown in Fig. 1. It will, of course, be understood that each tool- 85 receiving slot in the cover section must be provided with one of these retaining hooks, but one only is shown here for the purpose of illustration. The box section 1 is provided with a filler block formed of two layers or sections 8 and 9. For the heavier or larger tools both of said layers or sections are cut out to form the tool-receiving slots or recesses, but for the thinner or lighter tools one only of said sections or layers is 90 cut out to form the recesses for said tools. In this way the filler blocks may be cheaply manufactured; and the lower layer or section forms a bottom on which is supported the thinner or lighter tools. It is manifest 95 that if the thin tools were placed in recesses extending entirely through the filler block it would be difficult to reach down into said deep recesses to pick them up. For this reason it is desirable to place said tools in shallow slots. It will, of course, be understood 100 that where the filler blocks are formed of a single piece and are cut entirely through for

the reception of the thicker or heavier tools the slots or recesses so formed are too deep to receive the thin tools, and if the thin tools were placed in said deep slots they 5 would not be tightly held and would shift about and make a great deal of noise, besides damaging the box casings during the running of the automobile. It is also manifest that by forming the filler block of two 10 layers or sections both layers may be formed by independently sawing the slots and then bringing said layers together to form the complete filler. By this means the filler blocks may be formed cheaply. In the box 15 section 1 the wrench-receiving openings 10 are cut only through the upper layer so that the wrenches placed therein will rest on the upper surface of the lower layer of the filler. The lower layer of the filler extends across 20 the recesses 11 and 12 in the box section at various points, and serves as a supporting means for the tools placed in said recesses while permitting the thicker or heavier 25 parts of the tools to rest upon the felt secured to the bottom of the box section.

Cushion strips or sheets of felt 13 are arranged between the surfaces of the filler blocks when the box sections are closed, as shown clearly in Fig. 3, whereby the tools 30 will be inclosed between two cushioning layers, thereby rendering the box practically noiseless.

At suitable points the filler blocks are provided at their edges with sleeves 14, and 35 the walls of the box sections are punched inwardly, as at 15, to interlock said walls with the filler blocks, to thereby prevent the displacement or removal of the filler blocks from the box sections. To hold the 40 two parts of the box in their closed position a suitable spring latch device 16 is provided.

It will thus be seen that I provide a tool box of very simple construction which may be readily and cheaply manufactured. It is 45 also manifest that a tool box constructed as described herein will securely hold the tools in position and prevent noise which might be occasioned by the movement or shifting of the tools in the compartments or slots 50 made for them.

Having thus fully described my invention what I claim as new and desire to secure by Letters Patent is:

1. In a tool box the combination of two

sheet metal box sections hinged together 55 and of equal area, a lining of soft material for said box sections, a wooden filler block in each section and substantially filling the same and holding the lining in place, each block being formed with recesses extending 60 therethrough and exposing the soft lining, means carried by each block and adjoining the recesses therein for individually securing the tools in said recesses, and means for securing the blocks in place. 65

2. In a tool box the combination of two sheet metal box sections hinged together, a lining of soft material for said box sections, a wooden filler block in each section and substantially filling the same, each 70 block being formed with recesses extending therethrough, means carried by each block and adjoining the recesses therein for individually securing the tools in said recesses, and means for securing the blocks in place. 75

3. In a tool box the combination of two sheet metal box sections hinged together, a wooden filler block in each section substantially filling the same, a space being left 80 between the outer surface of said block and the edges of the side walls of the box sections whereby when the two box sections are folded a space is formed between the two filler blocks, each block being formed with tool-receiving recesses, means carried 85 by each block and adjoining the recesses for individually securing the tools in said recesses, said tool-securing means fitting in the space between the two filler blocks when the box sections are folded, and means for rigidly securing the filler blocks 90 in the box sections.

4. In a tool box, the combination with a sheet metal section, a lining of soft material for said section, a wooden filler block 95 in said section and substantially filling the same, said block being formed with a plurality of recesses, one or more of which extend through the block, and a cover for closing said section. 100

In testimony whereof I hereunto affix my signature in the presence of two witnesses this 7th day of January, 1911.

CHARLES W. BECK.
